DESIGN FOR A COMBINED TOOTHBRUSH, CASE, AND DENTIFRICE CONTAINER

Percy Gordon Watt, Palmerston, Ontario, Canada

Application January 28, 1943, Serial No. 109,376

Term of patent 14 years

To all whom it may concern:

Be it known that I, Percy Gordon Watt, a subject of the King of Great Britain and resident of the town of Palmerston, in the Province of Ontario, in the Dominion of Canada, whose post office address is Palmerston, in the Province of Ontario, have invented a new, original, and ornamental Design for a Combined Toothbrush, Case, and Dentifrice Container, of which the following is a specification, reference being had to

the accompanying drawing, forming part thereof.

The figure is a perspective view of a combined toothbrush, case and dentifrice container showing my new design.

I claim:

The ornamental design for a combined toothbrush, case, and dentifrice container, as shown.

PERCY GORDON WATT.
